ADOLPH J. NEEF, OF BROOKLYN, NEW YORK, ASSIGNOR TO THOMAS A. EDISON, INCORPORATED, OF WEST ORANGE, NEW JERSEY, A CORPORATION OF NEW JERSEY

TUNING INDICATOR FOR RADIORECEIVERS

Application filed August 9, 1930. Serial No. 474,271.

This invention relates to tuning indicators for radio receivers and the like and more particularly to indicators of the class described adapted to give a light signal when the tuning mechanism is adjusted to the position for selecting a desired station.

It is an object of this invention to provide apparatus of the class described in which the flash of light indicating the correct setting of the tuning apparatus may be obtained without the use of auxiliary contacts for closing the lamp circuit at particular positions of the dial.

It is a further object of this invention to provide apparatus of the class described in which the lamp which forms the source of the station indicating flash is maintained continuously illuminated when the receiver is in operation and the light from which is mechanically intercepted except when the tuning mechanism is set to a particular predetermined adjustment.

It is a further object of this invention to provide apparatus of the class described in which the light intercepting member is normally invisible and is provided with a removable opaque coating.

It is still a further object of this invention to provide apparatus of the class described embodying means operable from the exterior of the receiver housing for removing the opaque coating from the light intercepting member.

It is still a further object of this invention to provide apparatus of the class described so arranged that a considerable area of the indicating dial may be illuminated thereby.

Still other objects and advantages of my invention will be apparent from the specification.

The features of novelty which I believe to be characteristic of my invention are set forth with particularity in the appended claims. My invention itself however both as to its fundamental principles and as to its particular embodiments will best be understood by reference to the specification and accompanying drawings, in which

Fig. 1 is a side elevation of the tuning indicator according to my invention;

Fig. 2 is a side elevation thereof showing the opposite side from that shown in Fig. 1; Fig. 3 is a longitudinal sectional view thereof;

Fig. 4 is a detail sectional view showing 55 the indicating dial, the light intercepting member and the scraping mechanism;

Fig. 5 is an elevation view in partial section, showing the same;

Fig. 6 is a rear elevation of one form of 60 scraper mechanism, and

Fig. 7 is a front elevation showing the dial and escutcheon plate of a radio receiver according to my invention.

Referring now more particularly to the 65 drawings, 1 is the bracket on which the indicator mechanism is carried and comprising a down-turned base portion 2 by means of which the tuning indicator mechanism may be secured to the baseboard or frame. 70 The upstanding portion of the bracket 1 is provided with a U-shaped cutout 3 for receiving and rotatably supporting the driven shaft 4 of the tuning indicator. The said shaft may be hollow, if desired, and is provided 75 with an annular groove 6 for positioning the shaft in the bracket 1. Suitably secured on the end of the shaft there may be provided the driven wheel 5.

The shaft 4 is provided with a shoulder 7 80 to receive a disc 8 having a peripheral flange 14 and cut away at 13 over more than half its circumference. The indicating dial which in the form shown is a peripheral drum member 15 is secured to the flange 14 of disc 8 85 and is preferably divided peripherally into two coextensive peripheral sections side by side, one of which may be provided with permanent graduations and a scale and the other of which is preferably left blank and provided with a roughened surface adapted to be marked with a pencil.

The member 15 is preferably translucent and the rear side may be coated with a pigment or coloring matter over the markable portion thereof, whereby when light falls upon it from the rear it is illuminated and assumes a different color.

The shaft 4 is also provided with a second shoulder 19 to receive a second disc 9. Disc 100

9 is likewise provided with a peripheral flange portion 10 and carrying a drum 11 which may be of celluloid or other suitable translucent material provided on its outer 5 surface with an opaque coating 12. The coating 12 is removable and is applied in such a way that it may be easily scratched off. Printer's ink has been found to be a suitable coating but it will be understood that other 10 materials may be utilized.

The disc 9 is provided with a radial slot 9a for permitting the disc 9 and the drum 12 attached thereto to be slid into position on shaft 4, and disc 8 carries studs 8a and 8b 15 against which disc 9 abuts to fix its position. The assembly may be locked in position by means of a spring locking plate 16 having a radial slot 17 and having a finger piece 18 struck up therefrom. The plate 16 is preferably slightly dished so that when inserted in 20 position the discs 8 and 9 and the locking plate 16 are firmly but removably held in position upon shaft 4.

The mechanism for scraping or scratching a line through the coating 12 on drum 11 25 is supported from bracket 1 by means of a bracket 25 secured to the casing of the scraping mechanism and secured to the bracket 1. The position of the scraping mechanism may 30 be adjusted through the medium of slot 26 in bracket 25 and clamping screws 27 and 28 passing therethrough. The bracket 25 has an angularly offset portion 29 extending across the face of member 11 and having a 35 central slot 29a through which light may fall upon member 15. The housing for the scraping mechanism 30 is provided with an end portion 31 engaging the cover 32 and a shaft 33 extends therethrough provided with 40 a pin 34 and carrying an eccentric 35. For the purpose of holding the shaft rotatably in position in the housing there may be provided a leaf spring 38 having its ends positioned within stirrups 38a and 38b. A washer 45 39 may be positioned around shaft 33 and a pin 40 passed therethrough, whereby it will be seen that shaft 35 is held resiliently in position. Mounted upon the slider 36 there is provided a scraper 41 terminating in a blade 42 and having one or more bends 50 therein as at 43 and rigidly secured to the slider 36 as at 44. The casing is depressed as at 45 to engage the bend 43 in the scraper 41 whereby it will be observed, upon rotation of shaft 33, as by a screw driver inserted in the notch in the outer end of the shaft, eccentric 35 is rotated carrying with it slider 36 to the left as shown in Fig. 3, thereby forcing 55 the scraper 41 inward until the blade 42 comes in contact with member 11. Continued rotation of the shaft 33 causes the scraper blade to travel across the face of the member 11, scraping away a portion of the coating 12 and leaving a translucent line 60

on the member 11 as more particularly shown in Fig. 5.

A lamp bracket 50 terminating in spring clips 51 and 52 carries an offset portion 55 to which is attached socket 56 for lamp 57. 70 Also socket 53 carrying lamp 54 is attached to bracket 50 in such manner that the spring clips 51 and 52 may be slid over the outer end of the bracket extension 29, thereby securing lamp 54 behind and in close proximity 75 to member 11 and lamp 57 behind and in close proximity to member 15. The spring clip 51 may also be provided with an extending and down-turned portion arranged to operate as a shield to prevent light from lamp 80 57 falling on the portion of member 15 to be illuminated by lamp 54.

For the purpose of driving the tuning mechanism there may be provided a main shaft 59 carried in ears 60 and 61 mounted 85 upon the base portion 2 of bracket 1. Shaft 59 may carry a screw threaded member 62 and collars 62a and 62b. The bracket 1 may also be provided with an offset area 68 having 90 an opening in which there is mounted a sliding member 67 carrying idler pulleys 65 and 66. A member 69 is biased downwardly by a suitable spring in order to maintain the tension on the driving cord which passes over the periphery of pulley wheel 5 over the pulleys 65 and 66 and one or more times around the threaded member 62, whereupon it will 95 be seen that by rotation of shaft 59 the movement is transmitted to pulley 5, thence to shaft 4 and thence to the tuning apparatus 100 coupled thereto in any suitable manner.

In operation, the tuning mechanism and the tuning instrumentalities coupled thereto are preferably arranged within the housing diagrammatically indicated as at 70 and through which shafts 59 and 33 project. Also the housing is provided with a pair of windows 71 and 72, one of which exposes to 105 the graduated central portion of member 15, the other of which exposes the markable portion of member 15. The tuning apparatus is adjusted by means of shaft 59 until the desired station is tuned in, whereupon the shaft 33 may be rotated to cause the scraper blade 42 to inscribe a line on member 11. If the lamp 54 has previously been illuminated by means of a switch, which for example may be connected with the on and off switch of the receiver, the portion of the markable part of dial 15 observable through window 72 will 110 now be illuminated and the user may inscribe on the dial 15 the call letters of the station. 115

As the tuning is varied the translucent line on member 11 passes out of register with lamp 54 and window 72 and the portion of the dial 120 observable through window 72 is no longer illuminated.

In order to obtain a clean cut flash of light the lamp 54 is preferably placed immediately 125 adjacent and behind member 11 and the width 130

of the scraper blade 42 is made such that the angle subtended at the source of illumination, that is the filament of the lamp, corresponds with the angle subtended at the filament of the lamp by the width of window 72, in the direction of dial motion, whereby when the shaft 33 is operated to scrape a line on member 11, the entire area of dial 15 visible through window 72 is illuminated, and any change in adjustment of the tuning mechanism, even through a small amount, causes a portion of the light which would otherwise fall on the portion of the dial 15 visible through window 72 to be intercepted by the coating 12, whereby it will be seen that by adjusting the tuning mechanism until the entire area of dial 15 observable through window 72 is illuminated a very precise adjustment of the tuning mechanism is had. Also it will be seen that once having located a desired station and indicated its presence by operation of the scraper and by marking the call letters on dial 15 through window 72 the station may be tuned in easily, quickly and accurately at any subsequent time.

While I have indicated the members 11 and 15 as peripheral or drum members concentric or coaxial with respect to each other and movable simultaneously, it will be understood that the principles herein discussed may be utilized with circular dials, sliding scales or the like, and that modifications and changes may be made without departing from the spirit and scope of my invention as will be understood by those skilled in the art.

1. A tuning indicator for radio receivers and the like, comprising, in combination, a movable translucent indicating member, a second movable translucent member having an opaque portion which is adapted to be rendered translucent at a selected point, said portion being disposed adjacent and behind said first member, and a source of light disposed behind said portion of said second member.

2. A tuning indicator for radio receivers and the like, comprising, in combination, a movable translucent indicating member, a second movable translucent member having a portion disposed adjacent and behind said first member, and having a removable opaque coating, and a source of light disposed behind said portion of said second member.

3. A tuning indicator for radio receivers and the like, comprising, in combination, a movable translucent drum indicating member, a second movable translucent drum member having an opaque portion which is adapted to be rendered translucent at a selected point, said second member being disposed within said first member, and a source of light disposed within said second member.

4. A tuning indicator for radio receivers and the like, comprising, in combination, a movable translucent drum indicating mem-

ber, a second movable translucent drum member having an opaque portion which is adapted to be rendered translucent at a selected point, said second chamber being disposed within said first member and coaxial therewith and a source of light disposed within said second member.

5. A tuning indicator for radio receivers and the like, comprising in combination, a movable translucent drum indicating member, a second movable translucent drum member having an opaque portion which is adapted to be rendered translucent at a selected point, said second member being disposed within said first member and movable synchronously therewith, and a source of light disposed within said second member.

6. A tuning indicator for radio receivers and the like, comprising, in combination, a movable translucent drum indicating member, a second movable translucent drum member having an opaque portion which is adapted to be rendered translucent at a selected point, said second member being disposed within said first member and movable synchronously therewith, and a source of light disposed within said second member and in immediate proximity to said opaque portion.

7. A tuning indicator for radio receivers and the like, comprising, in combination, a movable translucent indicating member, a second movable translucent member, having a removable opaque coating, and having a portion disposed adjacent and behind said first member, and a source of light disposed adjacent and behind said portion of said second member.

8. A tuning indicator for radio receivers and the like, comprising, in combination, a movable translucent indicating member, a second movable translucent member having a removable opaque coating, and having a portion disposed adjacent and behind said first member, a source of light disposed adjacent and behind said portion of said second member, and means for removing a portion of said opaque coating from said second member.

9. A tuning indicator for radio receivers and the like, comprising, in combination, a housing, a movable translucent indicating member disposed within said housing, and having a portion exposed to view through an opening in said housing, a second movable translucent member having a removable opaque coating and having a portion disposed adjacent and behind said first member, a source of light disposed adjacent and behind said portion of said second member, means for removing a portion of said opaque coating from said second member, and means operable from the exterior of said housing for operating said removing means.

10. A tuning indicator for radio receivers and the like, comprising, in combination, a housing, a movable translucent indicating mem-

- drum disposed within said housing and having a portion exposed to view through an opening in said housing, a second movable translucent drum disposed within said first drum and having a removable opaque coating, a source of light disposed within said second drum, and means for removing a portion of said opaque coating from said second drum.
- 10 11. A tuning indicator for radio receivers, and the like, comprising, in combination, a housing, a movable translucent indicating drum positioned within said housing and having a portion visible through an opening 15 in said housing, a second movable translucent drum disposed within said first drum and having a removable opaque coating, a source of light disposed within said second drum, means for removing a portion of said opaque 20 coating from said second drum, and means operable from the exterior of said housing for operating said removing means.
12. A tuning indicator for radio receivers and the like, comprising, in combination, a 25 housing having an aperture therein, a movable translucent indicating member positioned within said housing and having a portion visible through said aperture a second movable translucent member having a 30 removable opaque coating disposed within said housing and having a portion disposed behind the visible portion of said first member, a source of light positioned behind said portion of said second member, and means for removing a portion of said opaque coating from said second member, from an area so chosen with respect to the position of said source of light and the position of said aperture that the entire visible portion of said first member is illuminated only for settings of said indicator corresponding to those desired.
13. A tuning indicator for radio receivers and the like, comprising, in combination, a 35 housing having an aperture therein, a movable translucent indicating member positioned within said housing and having a portion visible through said aperture, a second movable translucent member having a removable opaque coating disposed within said housing and having a portion disposed behind the visible portion of said first member, a source of light positioned behind said portion of said second member whereby light which would fall on the visible portion of said first member is intercepted by said second member, and means for removing a portion of said coating at desired settings of said indicator to permit said visible portion of said first member to be illuminated at said settings, said means being arranged to remove said coating over a width on said second member such that the angle of divergence of the beam of light passing therethrough is just sufficient to illuminate the width of said
- first member visible through said aperture.
14. A tuning indicator for radio receivers and the like, comprising, in combination, a housing having an aperture therein, a movable translucent indicating member positioned within said housing and having a portion visible through said aperture, a second movable translucent member having a removable opaque coating disposed within said housing and having a portion disposed behind the visible portion of said first member, a source of light positioned behind said portion of said second member whereby light which would fall on the visible portion of said first member is intercepted by said second member, and means for removing a portion of said coating at desired settings of said indicator to permit said visible portion of said first member to be illuminated at said settings, said means being arranged to remove said coating over a strip the width of which subtends an angle at the source of light substantially equal to the angle subtended at said source by the width of the visible portion of said first member.
- This specification signed this 7th day of August, 1930.
